INCINERATOR FIRING ELEMENT

Rowland P. Sword, Philadelphia, Pa., assignor, by
mesne assignments, to The Electric Incinerators
Corporation, a Corporation of Pennsylvania

Application April 29, 1931. Serial No. 533,641

1 Claim. (Cl. 219—19)

My invention relates to a new and useful improvement in electrically fired incinerators, and has for its object to provide an incinerator in which the firing of the material placed therein will be effected by an electric heating unit so constructed and mounted that it will not only be effective in igniting combustible material placed within the incinerator but will protect the heating element against damage and from contact with the combustible material before and after firing.

A further object of my invention is to provide an incinerator in the construction of which an outer casing is utilized and an inner fire resisting lining is so positioned within the casing as to form air spaces between the lining and the casing to prevent undue radiation of heat in order that the incinerator may be used within doors, without danger of causing fire or over heating the room in which it may be located.

A further object of the invention is to so construct such an incinerator that the entire front thereof may be opened to give free and unobstructed access to the interior for cleaning and repairs.

A still further object of the invention is to provide for connecting the combustion chamber of the incinerator with a chimney flue or other such outlet for the smoke, to provide draft inlets for bringing about effective combustion of the material placed within the combustion chamber and also to provide for the ready removal of the ashes falling through the grate.

With these and other ends in view, this invention consists in the details of construction and combination of elements hereinafter set forth and then specifically designated by the claim.

In order that those skilled in the art to which this invention appertains, may understand how to make and use the same, I will describe its construction in detail, referring by numerals to the accompanying drawings forming a part of this application; in which:—

Fig. 1 is a plan view of my improved incinerator.

Fig. 2 is a front elevation of Fig. 1, partly broken away and sectioned to show the interior construction, heating unit and tilting grate.

Fig. 3 is a central longitudinal section on an enlarged scale of the heating unit as assembled.

Fig. 4 is a central longitudinal section of the upper portion of the heating unit prior to the heating element being installed therein.

Fig. 5 is a view similar to Fig. 4, of the lower portion of the heating unit.

Fig. 6 is an end view of Fig. 3.

Fig. 7 is a cross section on the line 7—7 of Fig. 3.

In carrying out my invention as herein embodied, 10 represents a casing of sheet metal or other suitable material, preferably rectangular in plan and within this casing is positioned a lining structure 11 of high heat resistance, the casing being of larger dimensions than the lining structure so as to form the space 12 to prevent the heat from the outer surface of the lining from radiating directly into the room where the incinerator is installed and in order that the temperature of this casing may be kept at a low point, the space 12 has leading therefrom a flue 13, said flue surrounding the smoke pipe 14, the latter leading from the interior of the combustion chamber while the former leads only from the air space, both being intended for connection with the chimney flue; the lower ends of the air space being left open or having inlets thereto for supplying free air to said space and causing a constant circulation of air within the space when the incinerator is heated up.

15 represents a door which is hinged to the casing by the hinges 16, only one of which is shown in Fig. 2, and this door is lined with similar material to the lining 11 so that when the door is closed the combustion chamber 17 will be in condition to receive and hold the material to be burned and the lower portion of the air space will be completed. This door is provided with a latch 18 for engagement with the keeper 19 so as to hold the door in its closed position, but permit the ready opening thereof. 20 represents the charging door which is hinged to the upper portion of the casing as at 21 and 22, and this door is also provided with a latch 23 for holding it closed, and also carries a lining, here not shown, such lining being similar to lining 11 for the same purpose.

Thus it will be seen that free access may be gained to the interior of the incinerator by the opening of the doors 12 and 20.

24 represents what I term as the firing box which is here in the form of a rectangular casting opened at the top and bottom and provided with the flanges 25, which latter rest upon the angle iron frame 26, whereby the box is positioned and supported within the combustion chamber and within this firing box is located the heating unit 27, said heating unit being composed of a bottom member 28 and a top member 29, the bottom 28 is preferably semi-circular, the two ends extending above the body thereof and having the semi-circular openings 30 therein, and also hav-

95

100

105

110

ing the cross ribs 31 and the flange 32 while the top 29 likewise has the semi-circular openings 33 in the end walls thereof so that when the top is positioned upon the bottom these semi-circular openings 30 and 33 coincide to form circular openings or holes for the purpose hereinafter explained. The top is also provided with a rib 34 through which a circular opening 35 is formed, this last named rib is provided with a flange 36 10 which serves as a seat for the electrical insulating block 37 one end of said block having a circular hub 38 which fits in the hole 35.

An electrical insulating block 39 is set in the top 29 and positioned by the hub 40 thereof passing through the hole formed by the semi-circular openings 30 and 33 and when the top 29 is placed upon the bottom 28, these blocks rest upon the cross ribs 31 carried by the bottom.

42 is the heating element, the ends of which 20 are set in the sockets 43 and there held by the pressure of the spring 44 exerted upon the rod 45 through the washer 46 upon which latter, one end of the spring is seated, the opposite end of said spring being seated upon the electrical insulating block 47, the hub of which passes 25 through one of the holes formed by the semi-circular openings 30 and 33. The rod 45 passes through the blocks 37 and 47, its outer end being threaded for the reception of the nuts 48 30 thereto, for securing the end of one lead of the circuit 49 to this rod and the opposite socket 43 is mounted on the conducting rod 50 which passes through the insulating block 39, the outer end of said rod being threaded for the reception 35 of the nuts 51 for securing the other lead of the circuit 49 to said rod.

When the heating unit is assembled as has been described, one end thereof is passed through a suitable opening in the firing box 24 until said 40 end also passes through a suitable opening in the opposite wall of said box and the flanges 32 and 32a are brought into contact with the box after which the collar 52 is secured in place around the two members of the heating unit by the set screw 45 53 thereby holding the heating unit in position as clearly shown in Fig. 2. It being understood that the collar is passed over the end of the heating unit as the latter is being passed in to the firing box.

50 54 represents a tilting grate which is pivoted at 55 and 56 within the firing box, the stem 57 of said grate extending through the lining and casing of the incinerator for the convenient application of the shaker crank 58 and beneath this 55 grate is positioned a sliding ash tray 59 it having a handle 60 for the easy manipulation of said tray and this tray is for the purpose of catching the ashes which may fall through the grate or

60

65

70

75

which may be precipitated by the tilting of the grate.

The leads of the circuit 49 pass to a time switch box 61 so that the duration of the current passing through the heating elements may be predetermined and automatically cut off at the proper time.

80 From the foregoing description, the operation of my improved incinerator will be obviously as follows.

85 Refuse material being introduced into the combustion chamber through the door 20, the time switch 61 is set for the predetermined passage of the current through the heating element, and this passage of the current will produce sufficient heat within the enclosed heating unit for firing 90 this material through the openings 62 assisted by the upward flow of air through the slot 63 which tends to force the heat generated within said unit through these openings, but said openings are too small to permit a sufficient amount of the refuse to gain access of the heating unit to interfere with the operations thereof.

95 When the contents of the combustion chamber have thus been initially fired, it will continue to 100 burn by the draft passing upward through the grate and the smoke and fumes from this combustion will pass through the pipe 14 to the chimney flue and heating of the lining from this combustion will set up a vigorous circulation of 105 air within the space 12, the heated air passing off through the pipe 13 to the chimney flue while fresh air enters at the bottom of said space.

110 I have found in practice that an incinerator built in accordance with my invention may be installed in a dwelling permitting the burning of old refuse without permitting any smoke or odor to escape into the building and without giving off sufficient heat to inconvenience the occupants of 115 said building or in any way increase the fire risk.

120 Of course, the invention is not to be limited to the exact details of construction as herein shown, as said structural details may be varied within the limits of the appended claim without departing from the spirit of the invention.

125 Having thus fully described my invention, what I claim as new and useful is:—

A firing element for use in an incinerator of the character described, comprising a two part 130 housing, the bottom having its ends extended above the body thereof and also having cross ribs and an air inlet formed therein; the top being shorter than said bottom so that the former may be seated between said extended ends, said top also having heat outlet holes and a supporting rib formed therein.

ROWLAND P. SWORD.
